UNITED STATES PATENT OFFICE.

LOUIS ANDERSON, OF CAMDEN, NEW JERSEY.

DESIGN FOR A COMBINATION SMOKING-TABLE.

49,170.

Specification for Design.

Patented June 13, 1916.

Application filed March 28, 1916. Serial No. 87,364. Term of patent 7 years.

To all whom it may concern:

Be it known that I, LOUIS ANDERSON, a subject of the King of Norway, residing at Camden, in the county of Camden, and State of New Jersey, have invented a new, original, and ornamental Design for a Combination Smoking-Table, of which the following is a specification, reference being had to the accompanying drawing, forming part thereof.

Figure 1 is a perspective view of a com-

bination smoking table embodying my design. Fig. 2 is a similar view looking at the device at a different angle.

I claim:

The ornamental design for a combination smoking table, as shown.

LOUIS ANDERSON.
